UNITED STATES PATENT OFFICE

JAMES H. HARDEN, OF TOWANDA, PENNSYLVANIA.

MAIL-CRANE.

SPECIFICATION forming part of Letters Patent No. 322,709, dated July 21, 1885.

Application filed June 11, 1885. (No model.)

To all whom it may concern:

Be it known that I, JAMES H. HARDEN, a citizen of the United States of America, residing at Towanda, in the county of Bradford and 5 State of Pennsylvania, have invented certain new and useful Improvements in Supports for Mail-Bags; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification.

15 My invention relates to certain new and useful improvements in cranes for holding mail-bags so that they can be readily taken therefrom by means attached to a car; and my invention consists in the construction and combination of the parts, as will be hereinafter 20 fully set forth, and specifically pointed out in the claims.

In the annexed drawing I have illustrated my invention by a vertical sectional view, in 25 which A represents a suitably-constructed base, which serves as a support for an upright column, B, which may be either rectangular or otherwise shaped in cross-section. The opposite sides of the column are provided with 30 openings a, which extend from the base upwardly, and near the top of said column openings b are provided. Near the inner side of said openings are located pulleys or rollers c, which extend transversely across the openings 35 b, and are suitably grooved, in which grooves lie the cords C C. A column, B, is provided centrally with a vertical partition, F, which extends from the lower portion of the base upwardly to a point near the openings b, said 40 partition dividing the column into two parts. The outer edge of the column is provided, near its central portion, with notches N N', above and below which are attached, by means of 45 hinges H, arms A', the inner ends of said arms being beveled, as shown, so that when the same assume a horizontal position their ends and upper and lower edges will enter the notches, so as to have a firm bearing therein. To the upper arms A' are attached flexible connections or cords C, which pass over the pulleys 50 c, and pass from thence downwardly into one

of the vertical openings in the column, the end of said cord having attached thereto a sliding weight, W. To this weight and the lower arm is pivotally attached a rod, R, the lower end 55 of which passes through the opening a in the column, after which it is pivotally connected to the weight. The ends of the arms A' are provided with bent hooks P, which pass through the ends of the arms, and are provided with 60 horizontal portions, which are adapted to enter the straps attached to the ends of the mail-bag. The pins P can turn in the openings in the ends of the arm through which they pass, so that their horizontal projecting portions 65 can be turned in either direction, so that the mail-bag can be removed therefrom by a train going in either direction, and by providing the column with arms on both sides which operate independently of each other the de- 70 vice may be placed between the tracks, so that more than a single support will be unnecessary.

The operation of my invention is as follows: By either raising the lower arm or depressing the upper one both arms can be brought to a 75 horizontal position, and when in this position the mail-bag can be hung upon the hooks in a position to be removed by the passing train. It will be noted that when the mail-bag is attached to the ends of the arms it will be held 80 there securely without danger of accidental displacement. When the mail-bag is removed by a passing train, the upper arm will immediately be raised, and is assisted in said movement by the weight of the lower arm, said arm 85 being attached to the weight W by the rod R.

I claim—

1. In a mail-bag crane, a hollow support in which is located a sliding weight, and arms pivoted to the exterior thereof and connected to 90 said sliding weight, substantially as shown, and for the purpose set forth.

2. In combination with a suitable vertical support, arms A', pivoted thereto, a flexible connection attached to the upper arm and to 95 a sliding weight, and a rigid connection pivotally connected to the lower arm and weight, substantially as shown, and for the purpose set forth.

3. In a device for supporting mail-bags for the 100 purpose set forth, a hollow support or column having a vertical partition, and pivoted arms

attached to the opposite sides thereof, said arms being connected to sliding weights, whereby they will normally assume a vertical position, substantially as shown, and for the purpose set forth.

4. In a mail-bag support, a vertical column provided with a transverse partition, openings *a b* through the same, as shown, rollers located opposite the openings *b*, and arms *A'*, hinged or pivotally connected to the column and provided with flexible connections *C*, attached to a sliding weight, substantially as shown, and for the purpose set forth.

5. In a mail-bag crane, the combination, with the column *B*, having a vertical partition,

of an upper arm pivoted thereto and provided with a flexible connection, *C*, which passes over a roller, *c*, the lower end of said flexible connection being provided with a weight, *W*, and a lower arm having attached thereto a rod, *R*, which passes through an opening in the column and is pivotally connected to the weight *W*, the parts being organized substantially as set forth.

In testimony whereof I affix my signature in presence of two witnesses.

JAMES H. HARDEN.
